UNITED STATES PATENT OFFICE.

WILLIAM C. WINFIELD, OF WARREN, OHIO, ASSIGNOR TO THE WINFIELD MANUFACTURING COMPANY, OF SAME PLACE.

LANTERN.

SPECIFICATION forming part of Letters Patent No. 447,549, dated March 3, 1891.

Application filed February 23, 1889. Serial No. 300,819. (No model.)

To all whom it may concern:

Be it known that I, WILLIAM C. WINFIELD, a citizen of the United States, residing at Warren, in the county of Trumbull and State of Ohio, have invented certain new and useful Improvements in Lanterns; and I do hereby declare that the following is a full, clear, and exact description of the invention, which will enable others skilled in the art to which it appertains to make and use the same.

My invention relates to improvements in lanterns; and the object of the invention is to provide a lantern with improved facilities for removing the globe and for lighting and filling the lantern, as well as to simplify and improve the construction of the guard, all substantially as shown and described, and particularly pointed out in the claims.

Referring to the drawings, Figure 1 is a side view of a lantern embodying my improvements, the air-tube at the near side being broken away and the globe tilted as for removal. Fig. 2 is a front elevation of a lantern constructed as in Fig. 1, except that the side wires are movably connected with the canopy, and the guard and side wires are rigid with one another. Fig. 3 is a side elevation of the form shown in Fig. 2, with the globe-rest swung laterally at the bottom on its pivot-link to facilitate lighting or filling. Fig. 4 shows the form of the pivot-link in connection with the burner-cap and side. Fig. 5 shows a side wire rigid on the globe-rest and pivotally and removably connected with the canopy. Fig. 6 shows a rigid connection of side wire on globe-rest and canopy and an intermediate joint—say about the middle of the wire. Fig. 7 shows side wires rigid on the guard and the canopy and jointed between these parts, which is equivalent to jointing at the guard. Fig. 8 shows a novel way of attaching the side wire to the canopy, so as to get pivotal connection with security of connection.

The invention, as above indicated, is confined more especially to the mechanism for tilting and swinging of the globe and to the guard for protecting the globe. To this end A represents the globe, and B the canopy therefor. The canopy is preferably provided with a slight neck or collar b, which fits loosely

on the center tube C, thus allowing the canopy to tilt, as seen in Figs. 1 and 3. The neck b is not really a material feature, as the canopy could be secured on the tube without it; but the connection of the canopy with the said tube need be such that the canopy may swivel, tilt, or turn, as well as slide more or less thereon, so as to adapt it to the lateral movements of the globe herein provided.

D are the side wires, which are here shown as connecting the guard and the canopy, Figs. 1, 2, and 3, and also as extending down to the globe-rest. These wires may be rigid with the canopy, as they are in Fig. 1, where they pivot on the guard, as at d, or they may be movably and detachably connected therewith, as seen in Figs. 2 and 5, or they may, of course, be pivoted on the canopy and not removable, as seen in Fig. 8. When a rigid connection is made between the side wires and the guard, as in Figs. 2 and 3, the said wires must have a jointed connection with the canopy on which the canopy can tip to allow the removal of the globe from the guard; but a perfectly rigid connection at the guard and on the canopy is admissible to make the adjustment seen in Fig. 3. In case the side wires are attached by joint or pivot to the canopy or are pivotally and removably connected therewith and rigid with the guard, as in Fig. 2, for example, or pivoted on both canopy and guard, the spring support or holder E of the globe about its top will serve to deflect or tilt the canopy when the globe is thrown out to the position seen in Fig. 3. This holder E bears upon the bead a around the top of the globe and has sufficient downward spring and pressure to answer this purpose, while at the same time it stays the globe laterally and presses it upon its rest F, so as to prevent shaking or rattling.

E' represents the globe-guard. In the construction of guards several things are desirable: first, that the least amount of wire should be used compatible with the protection of the globe, which promotes economy of manufacture; second, that the guard should not increase the space occupied by the lantern, and that the symmetry of structure in the lantern as a whole should be promoted. To this end I have made a guard with a hori-

zontal portion e , which passes around the swell of the globe somewhat above its center, and inverted V-shaped portions e' , connected at their apex e^2 with the horizontal wire and 5 at the base or lower extremities with the globe-rest F . The connections at both points are rigid, so as to make the globe rest and guard rigid with each other and movable together. In forming the guard the most convenient method may be adopted, and the horizontal portion may be made in part with the V-shaped portion or separately, and afterward soldered or otherwise fastened thereto.

The guard proper, it will be understood, 15 consists in the parts here described as constituting the guard, and though the side wires extend up along the outside of the globe they have no function behind the side tubes as guards, but serve merely as connections between the canopy and guard or globe rest, 20 whereby said parts are held together and the globe is secured to obtain firmness of position and the various adjustments hereinbefore mentioned.

25 Now in order to make the adjustments of the globe shown in Figs. 1 and 3 I employ a link or ring G , which is pivoted near the base of the burner at one side thereof, as g , and on the bottom of the globe-rest, as g' , 30 and has a straight or substantially straight pivot portion, so as to prevent lateral play of the globe between the side tubes when the parts are raised or tilted and to insure accurate seating of the globe-rest when it is 35 brought back to position. The extremes of both movements are shown in Figs. 1 and 3, and the canopy is so constructed at its connection with the center tube that it will bind or lock on the tube and prevent the parts 40 from swinging farther out at the base on the pivot-link than substantially as shown in Fig. 1. In this position the parts will rest and give ready access to the burner to remove the cap, trim the wick, and light, or to 45 fill the oil-reservoir, when the globe can be swung back and all the parts will automatically resume their proper positions. In these back-and-forth movements the globe pan and canopy move in unison to the same relative 50 inclinations and positions, and, as before stated, may have a rigid connection or a pivotal connection through the guard and side arms at different points, as shown and described.

55 In operation, with the construction shown in Fig. 1 it is only necessary to press upward on the handle-extension l of the globe-holder E to throw all the parts easily into the position shown in said figure. This is done by 60 bearing upward against the extension l —say with the thumb—while the fingers of the same hand bear downward upon the air-tubes. It is equally convenient and easy to carry the parts into the position seen in Fig. 3 with one hand as well as to carry them back again. 65 All these facilities and advantages, it will be observed, are obtained with a saving of ma-

terial as compared with the old form of lantern. When the parts are down in position—for example, as in Fig. 2—it is desirable to 70 have the globe-rest locked to the base or body of the lantern, so that in case the lantern is thrown upon its side or the like and the globe broken the rest F , burner-cap, and other parts connected with the burner will be held 75 firmly in place and danger from fire on this account averted. To this end I employ a spring-latch k , preferably fixed on the pivot-link G , connecting the globe-rest with the base, which engages with a catch k' on the 80 side tube. This is one form of a lock serving this purpose. Obviously many other forms might be suggested.

Throughout this description and the claims the word "wire" has been used as a generic 85 term to designate the construction of the side wires, guard, and other parts, and wire proper is best adapted to these purposes; but I desire it to be understood that the term is meant to include and cover such equivalents as 90 strips of metal, whether single, double, rolled, or twisted, and employed in the same relation and combination shown herein and described. Such change of metal of course is 95 obvious, and may be made, if preferred, without departing from the invention covered by the claims.

In Fig. 5 I show side wires rigidly connected with the globe-pan and pivotally and detachably connected with the canopy, the wire being bent at right angles to engage a spring-catch l on the canopy, which serves to hold the wires in place. In Fig. 6 the wires are rigidly attached to both canopy and globe-rest and jointed at l' about midway of their 105 entire length. In Fig. 7 the wires are rigid with the guard and the canopy and jointed intermediately of these parts. In Fig. 8 the side wire is shown as jointed in the canopy by forming a loop m in the canopy itself, and, 110 having passed the side wire through the loop, the end is bent at right angles to lock it thereon. These are a few of the modifications 115 that suggest themselves in carrying out my invention. Others might be given, but are not deemed necessary.

From the foregoing description the manner of throwing the globe into position, as seen in Figs. 1 and 3, is obvious. For example, the position in Fig. 1 is obtained by merely 120 raising the spring-holder E and slightly tilting the canopy, if desired, when the top of the globe may be pressed outward and the parts will tilt into the position shown in Fig. 1 and the globe can be lifted out. To get the position in Fig. 3 the hook k is released and the globe, guard, and canopy carried bodily upward. This movement will tilt the globe to one side at the bottom, owing to the position of the link or ring G with respect to the base 125 and the globe-rest. The canopy slides up on its support and tilts sufficiently to allow the necessary lateral movement at the base.

I do not broadly claim a canopy supported

on a central air-tube and adapted to slide and rock thereon at the same time or when the globe is swung laterally at its base, nor do I broadly claim the combination of a lantern-frame and a globe rest or holder having its upper end at all times secured to the lantern-frame and its lower end hinged to the base to swing laterally out of position.

Having thus described my invention, what I claim as new, and desire to secure by Letters Patent, is—

- 5 1. In a tubular lantern, a globe-guard having a horizontal upper portion and sides rigid with the globe-rest and said upper portion and a globe-rest pivoted at one side of its center to tilt laterally, in combination with a canopy and pivoted connections between the canopy and the globe-guard, substantially as described.
- 10 2. In a tubular lantern, a globe-rest having a pivot at one side on which it tilts and a guard rigid therewith, in combination with a canopy supported on a tube and free to slide and tilt thereon and pivoted side connections 15 uniting the canopy and the guard, substantially as set forth.
- 20 3. In a tubular lantern, a globe-rest and a canopy, in combination with connections of fixed lengths between the rest and canopy rigid with the globe-rest and provided with joints by which the canopy is free to tilt for the removal of the globe, substantially as set forth.

4. In a tubular lantern, a globe-rest and a link connected pivotally with said rest and the base of the lantern, in combination with a guard for the globe, a canopy, and pivoted side wires extending from the guard to the canopy, substantially as set forth.

5. In a tubular lantern, the lantern-base and the globe-rest and an intermediate link on which the rest has two pivot movements, in combination with a guard attached to the rest, a canopy, and pivoted side wires connecting canopy and guard, substantially as described.

6. In a tubular lantern, a central tube, a canopy on the said tube, a globe-rest, and a guard for the globe rigid with the rest, in combination with connections between said guard and canopy provided with joints to allow the globe-rest or canopy to be tilted, substantially as described.

7. In a tubular lantern, a globe-rest and a canopy, in combination with connections between the said parts rigid at their ends and jointed at or near the center to permit the tilting of the globe-rest and canopy, and a central tube on which the canopy tilts, substantially as set forth.

Witness my hand this 14th day of February, A. D. 1889.

WILLIAM C. WINFIELD.
